UNITED STATES PATENT OFFICE.

FRANCIS KERKA AND HENRY EDMUND LINENBROKER, OF LONDON, ENGLAND.

APPARATUS FOR WAVING NATURAL HAIR.

1,184,101.

Specification of Letters Patent. Patented May 23, 1916.

Application filed January 24, 1914. Serial No. 814,204.

To all whom it may concern:

Be it known that we, FRANCIS KERKA and HENRY EDMUND LINENBROKER, both subjects of the King of England, and residents of London, W., England, have invented an Improved Apparatus for Waving Natural Hair, of which the following is a specification.

This invention has for its object an apparatus for waving natural hair on the head.

The features which distinguish our invention from known hair waving apparatus consist in that the waving apparatus, as hereinafter more fully described, comprises a tube having openings and two coaxially disposed inner tubes whereby the center tube consists of three sleeves of different diameter which are welded together, and of which the largest is provided with a slot. Thus, the paper tube, by means of which the hair is introduced first of all in the known manner, is made to come in contact with the smallest sleeve only, whereas the greater part of the paper tube and consequently the hair remains free of contact with the other two sleeves so that naturally only a small part of the said paper tube and hair is immediately heated. In this way it is then possible to dry the hair near its roots simultaneously with or sooner than the ends of the hair, which is of the greatest importance.

In order to assist the description reference is made to the accompanying drawings, in which:—

Figure 1 shows an elevation, partly in section, of the heater; Fig. 2 shows a section through line A—B, Fig. 1.

The electrical heater consists in the main of an inner tube comprising three sleeves *a*, *b* and *c*, the said sleeves being of different diameter and welded together, one to the other. The largest sleeve, namely that designated by *a* is provided at *d* with a slot, the material forming the edges of the slot being bent outwardly and backwardly in such a manner that flaps *d*¹ are formed which

serve to guide and hold the said tube coaxially within a second tube *f*. A cylindrical mantle *g* flanged at *g*¹ also coaxial with the center tube and provided with perforations *p* and slots *p*¹, is adapted to receive the said center tube and the second tube *f* and is moreover so constructed that the flanged handle *h* can be detachably fixed at *h*¹ while washers *h*² and *h*³ between the flanged portion *g*¹ of the mantle *g* and that of the handle *h* allow of an open air space *s* for the purpose of keeping the handle cool.

The means for heating this apparatus may be of any known and suitable construction and arrangement and are therefore not shown nor intended to form part of this invention.

The aforesaid slot *d* in the sleeve *a* has for its object to allow the escape of hot gases produced by the heating of the damp or greasy hair introduced into the apparatus, the gases finally escaping through the perforations *p* and slots *p*¹ of the mantle *g*.

Having now fully described our said invention what we claim and desire to secure by Letters Patent is:—

An apparatus for waving natural hair on the head, comprising the combination with a perforated tube, flanged and slotted at opposite ends, of two coaxially disposed inner tubes of which the innermost tube consists of three sleeves of different diameters which are welded together, the largest of said sleeves being provided with a slot, and the material adjacent thereto being turned up and formed into flaps, and a handle mounted at the flanged top of the said outer tube, substantially as and for the purpose set forth.

In testimony whereof we have hereunto set our hands in the presence of two subscribing witnesses.

FRANCIS KERKA.

HENRY EDMUND LINENBROKER.
